CLAIM

[21] Appl. No.: 302,864

The ornamental design for a decorative glass panel, as
shown and described.

DESCRIPTION

[22] Filed: Jan. 30, 1989

FIG. 1 is a front elevational view of a decorative glass

[52] U.S. Cl. D25/103

panel showing our new design; and

[58] Field of Search D25/48, 138, 145, 155,
D25/156, 103, 104, 105; 52/171, 311, 455, 456;
248/38, 15, 210

FIG. 2 is an enlarged fragmentary cross-sectional view
taken along line 2—2 of FIG. 1.

The glass panel is transparent, and the appearance of the
rear is essentially the same as the appearance of the
front.

FIG. 1

FIG. 2
